United States Patent Office

Des. 198,771
Patented July 28, 1964

198,771

FROZEN CONFECTION

David L. Hendrick, Commack, and John Russell Ridge,
New York, N.Y., assignors to Joe Lowe Corporation,
Englewood, N.J., a corporation of Delaware

Filed Jan. 23, 1964, Ser. No. 78,336

Term of patent 14 years

(Cl. D82—2)

FIG. 1

The essential features of the design reside in the portions shown in solid lines.

We claim:

The ornamental design for a frozen confection, substantially as shown and described.
